UNITED STATES PATENT OFFICE.

ELI HALIKMAN, OF BROOKLYN, NEW YORK, ASSIGNOR, BY MESNE ASSIGNMENTS, TO
HARRY BROMBERG, OF BAYSHORE, NEW YORK.

FIRE EXTINGUISHER.

Application filed June 25, 1926. Serial No. 118,535.

This invention relates to a fire extinguisher and particularly to the kind using a chemical, the object being to provide an improved structure which normally is supported at a convenient place and which may be quickly grasped and moved to near the fire for almost instant use.

Another object of the invention is to provide a fire extinguisher wherein the liquid container is removably held by a bracket and the discharge end is sealed while held in the bracket.

A further object, more specifically, is to provide a fire extinguisher for sprinkling extinguishing fluid, the arrangement being such that when used for extinguishing a fire, fluid will be sprayed or discharged in small jets while means are provided for permitting a quick filling.

20 In the accompanying drawing—

Figure 1 is a front elevation of a fire extinguisher disclosing an embodiment of the invention, the same being shown applied to a support.

25 Figure 2 is a side view of the structure shown in Figure 1, the support being shown in section.

Figure 3 is an enlarged fragmentary sectional view of the upper part of the extinguishing can and lid.

30 Figure 4 is a top plan view of the container with the cap removed.

Figure 5 is a bottom plan view of the container showing the gasket.

35 Figure 6 is an enlarged sectional view through a screw disclosing certain features of the invention.

Referring to the accompanying drawing by numerals, 1 indicates a support of any 40 desired kind, as for instance, a wall. Connected with the support 1 is a bracket 2 formed with a supporting bar 3, a spring clip 4 and a supporting spring clip 5. The bar 3 is provided with openings 6 and 7 for 45 receiving the respective screws 8 and 9 whereby the bracket is firmly clamped to the support 1. Preferably, the bracket is bent at point 10 and again at point 11 for providing an offset or shoulder 12 whereby 50 the bracket may be set further out from the support 1. Also, this arrangement permits the section 13 which merges into the top member 14 to be spaced from the support 1 and thereby present some space for the end 55 of the screw 15, which screw extends through

the cap 16 for supporting the same against section 14. The cap 16 is made from sheet metal and the side wall is bent back upon itself at 17 and then formed into a horizontal section 18 which merges into a closure 60 portion 19. This structure results in providing an annular recess 20 which is adapted to receive the gasket 21 which may be of cork or other desired material. The closure portion 19 is rounded somewhat at the lower 65 edge 22 so that it may readily enter the annular depression 23 and snugly fit the same so as to present an air-tight connection which is augmented by the action of the gasket 21 and the annular bead 24 formed on the top plate 25. This top plate is soldered or otherwise secured to the upper end of the container 26 and is provided with the annular depression 23 which merges into a bottom section 27 having a series of apertures 70 75 28. In forming these apertures they are punched so that the material will project upwardly when the parts are in the position shown in Figure 3. This will permit the liquid in the container to freely flow therefrom and be sprayed as it is discharged. At the center of the bottom 27, the material is pressed downwardly for forming an aperture and the downward portion or bur 29 is 80 threaded for receiving the threaded screw 30. This screw is provided with an aperture 31 85 of approximately the same size as the openings 28 whereby a proper distribution may be made of the liquid when the device is in use.

When it is desired to re-fill the device, screw 30 is removed and the re-filling liquid passed through the aperture from which the screw has been removed. The container 26, which may be of any size and length, is normally held near a central point by the clip 4 and the lower end by the clip 5. It will be noted that these clips do not encircle the container but extend approximately half way across the container whereby the container 90 95 may be grasped at the center or near the lower end and swung upwardly away from the lower end of bracket 2. This swinging movement will cause the annular depression 23 to leave the sealing portion 19 whereby the container is free and may be inverted so as to discharge the liquid therefrom. As the liquid is discharged in a rather large spray, it may be quickly distributed over a fire so as to secure a maximum result in a minimum 100 105 110

time. If all of the liquid or most of the liquid is used, screw 30 is removed and a new supply provided. After this has been done, the container may be readily placed back in position by passing the annular depression 23 over the sealing portion 19 and then springing the clip 5 until it engages the bottom of the container. The container is then pushed over to the correct position and if desired, may be struck on the bottom to force the same upwardly or the hand may strike the section 14 with a downward blow while the container is being held. This acts to cause a better seating of the parts whereby they will assume accurately the position shown in Figure 3. It will be noted that the gasket 21 is carried by the cap 16 and that the cap is held firmly against part of the bracket 2 so that the gasket is always in position for use.

What I claim is:

1. A bracket for supporting a container provided with a removable cap comprising a body adapted to be mounted in a vertical position having apertures near each end for receiving securing means and a top horizontal section, said body having a threaded aperture near said section, a screw member adapted to extend through said cap and into said threaded aperture for clamping the cap to the bracket, a pair of resilient arms carried by said body intermediate the ends, said arms being positioned to partly encircle said container to hold the container adjacent said body, and a spring carried by said body near the bottom, said spring adapted to act on said container to force the same against said cap.
2. A bracket for supporting a container provided with a removable cap comprising a body offset in one direction intermediate its

ends and offset in the opposite direction near one end whereby the body will be adapted to contact a vertical support at two points, said points being near the respective ends, said body having an aperture for receiving a securing member, said aperture being located at the point of greatest bend of the first offset whereby when said securing member is brought under tension the body may be brought under tension so as to prevent rattling, said body at the lower end being provided with an aperture for receiving a securing member, said body at the upper end being provided with a right angle extension, a threaded aperture adjacent the second offset, threaded means fitted into said threaded aperture for holding a cap against said extension, and a plurality of spring members for holding the container near said body with one end pressed against said cap.

3. A fire extinguisher comprising a container having an upper end piece provided with a central depression, an annular bead adjacent the upper part of the depression, a series of apertures at the bottom of the depression, said apertures being surrounded by upwardly extending spurs, said bottom being also provided with a threaded inwardly extending sleeve, a screw plug normally threaded into said sleeve for closing the same, a cap having a central depressed portion fitting into the depressed portion on the end of the container, said cap having an annular outer depending flange, which with said depending portion, forms an annular outer groove, and a gasket carried by said groove fitting over said annular bead whereby the bead will be partly embedded in the gasket for making a tight connection.
